United States Patent

Des. 240,363
Patented June 29, 1976

240,363

AQUARIUM STAND

Leslie J. Weigel, Cincinnati, Ohio, and Elmer A. Wolfzorn, Fort Thomas, Ky., assignors to Manual Arts Furniture Company, Cincinnati, Ohio

Filed Apr. 4, 1975, Ser. No. 565,268

Term of patent 14 years

Int. Cl. D6—06

U.S. Cl. D30—12

FIG. 1 is a perspective view of an aquarium stand embodying our new design;

FIG. 2 is a side elevational view thereof, the opposite sides being the same;

FIG. 3 is an end elevational view thereof, the opposite ends being the same;

FIG. 4 is a top plan view thereof;

FIG. 5 is a bottom plan view thereof; and

FIG. 6 is a perspective view similar to FIG. 1 but illustrating a modification of our design wherein the lower shelf is omitted.

We claim:

The ornamental design for an aquarium stand, as shown and described.
